MASAJI YOKOYAMA, OF SETAGAYA-CHO, JAPAN.

SYSTEM OF UNIFYING A GROUP OF CLOCKS.

Application filed May 25, 1926, Serial No. 111,480, and in Japan May 28, 1925.

This invention relates to a system for the unification of the face time of a group of clocks and is applicable to a plurality of clocks of arbitrary types.

According to this invention any one of the group is chosen as the leader clock and the rest as subordinate clocks. In each of the subordinate clocks, an electric motor and a switching device therefor are provided, and in the leader clock, a switching device for short-circuiting or opening the switching devices in the subordinate clocks is provided. By this arrangement the circuits of the motors in the subordinate clocks are collectively closed by means of the switching device provided in the leader clock, whereby two guide pins mounted on toothed wheels in mesh with each other operate slidably on a cam rod attached to the minute hand of a subordinate clock, slidably contacting therewith, symmetrically from both sides thereof. In this manner the minute hand of each of the subordinate clocks is brought to the position of the dial corresponding to that of the leader clock, the guide pins thereafter rapidly receding from the sphere of motion of the cam rod.

In the drawing annexed herewith, Figure 1 represents a diagram of electrical connections of the clock unifying system according to my invention.

Figure 2 shows the clock hand correcting mechanism in one of the subordinate clocks in conjunction with the controlling switch in the leader clock.

Figure 3 is a side view of a portion of the correcting mechanism showing the relations between the guide pins and the cam rod in a subordinate clock.

Figure 4 is a plan illustrating the limits of the position of the cam rod capable of being acted on by the guide pins.

Now referring more particularly to the characters and numerals on the drawing, in Figure 1, 1, 2, 3, 4 and 5 are clocks of arbitrary types and makes, among which any one, say 1, is chosen as the leader clock. It may not necessarily be the most accurate one. Then, the rest, 2, 3, 4 and 5 are to be all subordinate clocks.

Figure 2 shows the electrical connections between the leader clock and one of the subordinate clocks, say 2, and the hand correcting mechanism in the latter. The switching means in the leader clock consists of a cylindrical drum or slip ring 7 made of

an insulator and provided on the shaft of the minute hand 8 of the clock. The drum 7 has a metallic segment 9 of a narrow width embedded therein and is also provided with a pair of contacting brushes 10. The correcting mechanism in a subordinate clock comprises an electric motor 11 and two pinions 12, 13 of equal diameter meshing with each other and driven through a series of reducing gears by the motor. The pinions 12, 13 are provided with guide pins 14, 15 respectively. One of the pinions 13 has attached on its shaft a slip ring 16 consisting of a broad metallic portion 16^a and a narrow insulating portion 16^b. The mechanism also comprises a cam rod 17 attached to the shaft of the minute hand 18. The slip ring 16 is also provided with a pair of brushes 19 contacting therewith at the circumference thereof. The motor 11 is electrically connected by lines 20 to one of the supply lines 21 and the auxiliary line 23 respectively. The brushes 10 of the leader clock and the brushes 19 of each of the subordinate clocks are connected to one of the supply lines 22 and the auxiliary line 23 respectively.

On assembling the clocks, the hand 8 of the leader clock should be so adjusted that the position which it assumes when the brushes 10 touch the metallic segment 9 corresponds with the position of the hand 18 of the subordinate clocks when the respective cam rods 17 rest in the direction as they have been acted upon from the two opposite sides thereof by the guide pins 14, 15 as the pinions 12, 13 rotate in the opposite directions. Such corresponding positions of the hands 8 and 18 are illustrated in Figure 2.

Normally, the circuit of the motor 11 is broken at the brushes 19, the same being in contact with the insulating segment 16^b of the slip ring 16, and the whole correcting mechanism has nothing to do with the operation of the clock mechanism of the subordinate clock.

After the leader clock and the subordinate clocks have commenced their operation, at a certain time, the brushes 10 of the leader clock will come to contact with the metallic segment 9 of the slip ring 7. This will cause the short circuiting of the brushes 19 and consequently the completion of the circuits of the motors 11.

The motor will start and drive, through

the intermediary reducing gears, two oppositely rotating pinions 12 and 13, whereby the cam rod 17 will be brought to the central position with respect to the two pinions 12, 13 owing to the symmetrical circular motion of the guide pins 14 and 15, and the hand 18 is brought to the position corresponding to that of the hand 8 of the leader clock. Meanwhile the slip ring 16 will have 10 rotated and the brushes 19 will have come off the contact with the insulating portion 16^b and step upon the long metallic portion 16^a. As the result, the motor and consequently the whole correcting mechanism will 15 continue to operate, and it will come to rest only when the brushes 19 are again on the insulating portion 16^b. In this position, which is the position shown in Figure 2, guide-pins 14, 15 are entirely out of the 20 sphere of motion of the cam rod 17, so that they will not interfere with the operation of the clock mechanism.

The limit of error which can be corrected depends upon the circles of motion of the 25 guide pins 14, 15 and the distance of these circles from the axis of the hand 18. These relations are clearly indicated in Figure 4, the limiting angle being equal to α at each side of the central position of the cam rod 30 as shown in full lines. The positions of the pins 14, 15 shown in full lines indicate the positions at which the respective pins rest after each operation of the correcting mechanism. In actual construction, the appropriate 35 value of this angle is 35° at each side of the central position and corresponds to 6 minutes' error either side. In ordinary clocks, the error does not exceed 30 to 60 minutes per day. Therefore the above angle 40 would give a sufficient allowance for correcting the errors occurring in clocks of ordinary grade.

The short circuiting of the brushes 10 by the metallic segment 9 in the leader clock 45 should last only until the brushes 19 have come to contact with the metallic portion 16^a from the position in contact with the insulating portion 16^b. Therefore it suffices if the width of the metallic segment 9 be 50 only very small.

The leader clock should be corrected at any suitable time at the minute hand. In this case, the slip ring 7 will displace together with the minute hand. In the meantime, however, all the subordinate clocks 55 will be in unison with the leader clock by the operation of the correcting mechanism. Thus it will be seen that while it is desirable to employ as the leader clock one as accurate as practicable, it is not a factor which is absolutely essential. It is only necessary to correct the leader clock once in a while against a standard clock or otherwise.

In case the leader clock and the subordi-

nate clocks are of the type whose spring motor is wound by an electric motor, the same electric motor may be utilized to operate the time correcting mechanism, and it will not be necessary to make specially any 70 electrical connections except providing the auxiliary wire 23. In this case, the correcting mechanism will be operated each time when the winding of the spring motor takes place. 75

What I claim is:

1. A device for unifying the face time of a plurality of clocks, comprising switching means associated with a rotating member of an arbitrary one of the clocks chosen as the leader clock, the part of the device incorporated with any one of the remaining clocks comprising a cam rod attached to the shaft of the minute hand, two pinions of equal diameter meshing with each other and each provided with a guide member to come into a sliding contact simultaneously with the said cam rod from opposite sides thereof, switching means connected mechanically in operating relation to one of the said pinions, 80 and an electric motor for driving the said pinions, the said pinions being sufficiently removed from the axis of the cam rod so that normally the guide members will not interfere with the operation of the clock 85 mechanism. 90

2. A device for unifying the face time of a plurality of clocks, comprising switching means attached to the shaft of the minute hand and another switching means electrically connected in series with the first named switching means and attached to a more slowly rotating shaft of an arbitrary one of the clocks chosen as the leader clock, the part of the device incorporated with any one of the remaining clocks comprising a cam rod attached to the shaft of the minute hand, two pinions of equal diameter meshing with each other and each provided with a guide member to come into a sliding contact simultaneously with the said cam rod from opposite sides thereof, switching means connected mechanically in operating relation to one of the said pinions, and an electric motor for driving the said pinions, the said 100 pinions being sufficiently removed from the axis of the cam rod so that normally the guide members will not interfere with the operation of the clock 105 mechanism. 110

3. A device for unifying the face time of a plurality of clocks, comprising a slip ring attached to the shaft of the minute hand of an arbitrary one of the clocks chosen as the leader clock, the part of the device incorporated with any one of the remaining clocks comprising a cam rod attached to the shaft of the minute hand, two pinions of equal diameter meshing with each other and each provided with a guide pin to come simultaneously into a sliding contact with the said 120 125 130

cam rod from opposite sides thereof, a slip ring provided on the shaft of one of the said pinions, a pair of brushes held in contact with the last named slip ring and an electric motor for driving the said pinions.

4. A system for unifying the face time of a plurality of clocks, one of which is arbitrarily chosen as the leader clock, which comprises an electric circuit between the leader clock and the subordinate clocks, switching means associated with a rotating member of the leader clock, each subordinate clock comprising an electric motor, a pair of pinions mechanically connected with said motor, guide members on said pinions, means carried by the shaft of the minute hand adapted to cooperate with said guide members on the pinions to adjust the minute hand to its proper position at predetermined intervals, and normally open switching means associated with one of the pinions, the motor being operable through the closing of either switching means.

5. A system for unifying the face time of a plurality of clocks, one of which is arbitrarily chosen as the leader clock, which comprises an electric circuit between the leader clock and the subordinate clocks, switching means associated with a rotating member of the leader clock, each subordinate clock comprising an electric motor, a pair of pinions mechanically connected with said motor, guide members on said pinions, means carried by the shaft of the minute hand adapted to cooperate with said guide members on the pinions to adjust the minute hand to its proper position at predetermined intervals, and normally open switching means associated with one of the pinions, the motor being operable through the closing of either switching means.

hand to its proper position at predetermined intervals, and normally open switching means associated with one of the pinions, the closing of the first-mentioned switching means functioning to complete the electric circuit through the motor to rotate the pinions and to close the second-mentioned switching means.

6. A system for unifying the face time of a plurality of clocks, one of which is arbitrarily chosen as the leader clock, which comprises an electric circuit between the leader clock and the subordinate clocks, switching means associated with a rotating member of the leader clock, each subordinate clock comprising an electric motor, a pair of pinions mechanically connected with said motor, guide members on said pinions, means carried by the shaft of the minute hand adapted to cooperate with said guide members on the pinions to adjust the minute hand to its proper position at predetermined intervals, and normally open switching means associated with one of the pinions, the closing of the first-mentioned switching means functioning to complete the electric circuit through the motor to rotate the pinions and to close the second-mentioned switching means, the interval during which the first-mentioned switching means is closed being relatively short as compared to the interval during which the second-mentioned switching means remains closed.

In witness whereof, I have hereunto signed my name.

MASAJI YOKOYAMA.
